NOTEBOOK CONSTRUCTION

Frank Stanley Schade, Holyoke, Mass., assignor to
 National Blank Book Company, Holyoke, Mass.,
 a corporation of Massachusetts

Application May 8, 1939, Serial No. 272,349

6 Claims. (Cl. 281—25)

This invention relates to an improved book and particularly to a combination of structure by which two book covers and connecting back portion may be bound at the back portion with a removable filler or pack of sheets. It is particularly useful as a small personal notebook for the pocket.

The prior books of this general sort are well-known so that anyone in the art will see the advantages in the structural combination of my invention from my following detailed disclosure of a preferred form.

In the drawing:

Fig. 1 is a perspective view of a notebook constructed according to my invention with the cover opened and the notebook ready for use;

Fig. 2 is a fragmentary end elevation of the notebook in closed position and showing certain features of construction;

Fig. 3 is a sectional view taken on line 3—3 of Fig. 2 but with the notebook filler and its coiled binder wire removed; and

Fig. 4 is a view similar to Fig. 3 but with the notebook filler and its coiled binder wire inserted.

The notebook combination is shown assembled and open in Fig. 1 and closed in Fig. 2. In the latter, the back portion is B and the covers are 9 and 10. These parts may be and preferably are made from a single strip of thin flexible material, as leather. Midway of the back portion and on opposite edges, I prefer to provide small slits 14. They are best seen in Figs. 3 and 4.

The pack of notebook sheets, generally called a filler, is 5. This pack has a coiled binding element 6 threaded through openings at the binding margin of the sheets. There are many well-known forms of such binding elements per se, and I do not desire to limit the present invention to any particular species of such element in my combination. I have shown the well-known helically coiled wire for this purpose; but a wire or other stiff flexible material might be coiled into other forms than helical coils and such type would serve my purpose, as will appear. Such a pack of bound filler sheets is so well-known that no further description of it is necessary.

The bound pack 5 is fastened to the back portion B by a hasp 8. It is this element in its relation with the others that gives the structural combination the desired function.

While variations may be made, the hasp 8 in its preferred form is best seen in Fig. 3. It consists in one piece of stiff wire, bent at the center into an eye 13, having two straight portions 8', two return bends 11 and 12, and two short portions 19.

The ends of the latter preferably have slight outward bends, as shown.

The hasp 8 is assembled on the back portion B by pushing eye 13 through a small opening 15, the edges of which are preferably spaced closely enough to crowd over the eye and then underlie the eye somewhat as a snap button. The two edges of back portion B are slipped into the oppositely arranged hook portions 19 at the ends of the hasp. Then the hasp has a grip at the back portion as seen in Fig. 3 and forms a centrally arranged back bone for the back portion, as seen in Fig. 2. This hasp will thus, in the form shown, serve as a narrow line of stiffening material from which line a single sheet of flexible material like thin leather will start to bend accurately so as to form the opposite curves of the back portion, from which the covers are hung.

It will be seen from Figs. 1 and 2 that while the back portion is curved and the covers strictly considered start from the opposite ends of the back portion, the covers will always tend to turn from a single hinge line located exactly midway of the curved back portion. Thus, the two covers have but one hinge line and that one located and supported by the stiff wire hasp, as a back bone. This arrangement results in a binding for a low cost book that will retain its original neat appearance for a long time.

The whole structure, as described, is flexible. To insert a filler pack 5 into this flexible binder, the portions 19 of the hasp 8 are hooked into the ends of the coiled wire 6 of the pack. The pack 5 is shifted to register centrally of the covers and then the eye 13 is buttoned into two adjacent coils 20, preferably so as to have these coils tighten sidewise against eye 13, thus serving as in Fig. 4 to position the parts 5 within the covers and prevent any lateral shifting of the coils. In this position the hasp has a sufficient grip on both the back portion connecting the covers and on the binder coils of the pack 5 with the result of clamping all parts together along the one hinge line mentioned above.

The improved book in its preferred form has now been fully disclosed. I claim as my invention:

1. A book of the class described comprising, a single sheet of flexible material to form two covers and connected back portion, a spring wire hasp extending across the back portion from side to side serving to predetermine one hinge line for bending the flexible material, the main portions of said hasp lying along the outside face of the flexible material, and provided at opposite ends 55

- with oppositely disposed hooks lying along the inside face of said material, and a small central button portion extending through the material from back to front, all for the purpose described.
5. A notebook construction consisting of a pack of notebook sheets bound along one edge by means of a coiled wire binding threaded through spaced binding holes in said sheets, a cover member to the inside surface of which said pack is removably fastened, and means for removably fastening said pack to said cover member, said means consisting of a wire hasp extending across the outside surface of said cover member along the fastening axis with its end portions extending through the cover to engage the coils of the binding wire and having integral positioning means formed between said end positions with said means extending through an opening in said cover to engage coils of the binding wire for the purpose described. 5
10. A notebook construction consisting of a pack of notebook sheets bound along one edge by means of a coiled wire binding threaded through spaced binding holes in said sheets, a cover member to the inside surface of which said pack is removably fastened and means for removably fastening said pack to said cover, said means consisting of a wire hasp extending across the outside surface of said cover member along the fastening axis with its end portions extending through said cover and having a rebent portion adapted to lie within the convolutions of said wire binding, said hasp having in addition, integral positioning means intermediate its end portions, which means extend through an opening in said cover and engage the coils of said binding wire for the purpose described. 10
15. A notebook construction consisting of a pack of notebook sheets bound along one edge by means of a coiled wire binding threaded through spaced binding holes in said sheets, a cover member to the inside surface of which said pack is removably fastened and means for removably fastening said pack to said cover, said means consisting of a wire hasp extending across the outside surface of said cover member along the fastening axis with its end portions extending through said cover and having a rebent portion adapted to lie within the convolutions of said wire binding, said hasp having in addition, integral positioning means intermediate its end portions, which means extend through an opening in said cover and engage the coils of said binding wire for the purpose described. 15
20. A notebook construction consisting of a pack of notebook sheets bound along one edge by means of a coiled wire binding threaded through spaced binding holes in said sheets, a cover member to the inside surface of which said pack is removably fastened and means for removably fastening said pack to said cover, said means consisting of a wire hasp extending across the outside surface of said cover member along the fastening axis with its end portions extending through said cover and having a rebent portion adapted to lie within the convolutions of said wire binding, said hasp having in addition, integral positioning means intermediate its end portions, which means extend through an opening in said cover and engage the coils of said binding wire for the purpose described. 20
25. A notebook construction consisting of a pack of notebook sheets bound along one edge by means of a coiled wire binding threaded through spaced binding holes in said sheets, a cover member to the inside surface of which said pack is removably fastened and means for removably fastening said pack to said cover, said means consisting of a wire hasp extending across the outside surface of said cover member along the fastening axis with its end portions extending through said cover and having a rebent portion adapted to lie within the convolutions of said wire binding, said hasp having in addition, integral positioning means intermediate its end portions, which means extend through an opening in said cover and engage the coils of said binding wire for the purpose described. 25
30. A notebook construction consisting of a pack of notebook sheets bound along one edge by means of a coiled wire binding threaded through spaced binding holes in said sheets, a cover member to the inside surface of which said pack is removably fastened and means for removably fastening said pack to said cover, said means consisting of a wire hasp extending across the outside surface of said cover member along the fastening axis with its end portions extending through said cover and having a rebent portion adapted to lie within the convolutions of said wire binding, said hasp having in addition, integral positioning means intermediate its end portions, which means extend through an opening in said cover and engage the coils of said binding wire for the purpose described. 30
35. A notebook construction consisting of a pack of notebook sheets bound along one edge by means of a coiled wire binding threaded through spaced binding holes in said sheets, a cover member to the inside surface of which said pack is removably fastened and means for removably fastening said pack to said cover, said means consisting of a wire hasp extending across the outside surface of said cover member along the fastening axis with its end portions extending through said cover and having a rebent portion adapted to lie within the convolutions of said wire binding, said hasp having in addition, integral positioning means intermediate its end portions, which means extend through an opening in said cover and engage the coils of said binding wire for the purpose described. 35
40. The structure of claim 3 with said intermediate positioning means consisting of a loop formed in said wire hasp in wedged relation between adjacent coils of said binding wire. 40
